UNITED STATES PATENT OFFICE.

JESSE C. MARTIN, JR., OF SAN FRANCISCO, CALIFORNIA.

BRICK DIE.

Application filed August 16, 1926. Serial No. 129,448.

The invention relates to dies for re-pressing brick and has as an object the provision of a die having means to form interlocking complementary projections and depressions upon opposite sides of the brick.

A further object of the invention is to provide a die having means to heat the same.

A further object of the invention is to provide a die having means to free the re-pressed brick from the projection and depression forming elements.

A further object of the invention is to provide a die having resilient means to free the pressed brick from the die and means separate therefrom to limit the action of the resilient means.

Further objects of the invention will appear from the following description when read in connection with the accompanying drawings wherein:—

Figure 1 is a side elevation partly in central vertical section showing the upper and lower die members;

Figures 2, 3, 4, 5, and 6, are horizontal sections on the corresponding section lines of Figure 1;

Figure 7 is a vertical section on broken section line 7—7 of Figure 1 showing the lower die member.

Figure 8 is a side elevation of a brick to be formed by the illustrative form of the invention shown in Figs. 1-7.

As shown, the device comprises an upper member 10 and a lower member 11. The upper member is shown as secured to a press member 12 by means of bolts 13, 14, and is shown as comprising a block 15 having a die member 16 secured thereto by cap screws 17, 18. The member 16 is provided with a face plate 19 secured thereto by cap screws 20, 21, the face plate having projection-forming depressions 22, 23, adapted to form interlocking projections or bosses upon the face of a brick.

To free the projections upon the brick from the depressions 22, 23, there are shown plungers 24, 25, normally projecting into the space in the depressions 22, 23, and limited in their projection therein by shoulders 26 formed by enlargements upon the plungers 27, which enlargements are housed in the chamber 28 in the die member 16. Coil springs 29 are shown to press the plungers 27 outwardly and these springs are shown as surrounding a reduced portion 30 of each

plunger 27, the ends of which reduced portions determine the amount of inward motion of the plunger into the die member. When the plungers are pressed inwardly, with the compression of the springs 29, to the limit of motion the faces 24, 25, will be flush with the bottoms of the depressions 22, 23.

Means for heating the die member 16, and by conduction the face plate 19, is shown in the form of chamber 31 in the die block having pipes 32, 33, for introduction and withdrawal of steam. As shown in Figure 1, the pipes 32, 33, enter the chamber 31 at the upper portion thereof and a baffle 34 extending downwardly from the roof of the chamber to a point above the floor thereof is provided to cause the steam to effectually heat the walls of the chamber.

The lower die block 11 is adapted to be secured to a press member, not shown, by cap screws 35, 36, and comprises the block 11 and a face plate 37.

To form interlocking depressions in one side of the brick to be formed, the lower die member 11 is shown as provided with depression-forming members 38, 39, shown as applied to the block 11 by screwthreaded projections 40 taking into correspondingly screwthreaded sockets in the block 11. The members 38, 39, are telescopically received in openings 41 in the face plate 37 and normally have their faces 42 standing flush with the face of the plate.

The face plate 37 is shown as pressed outwardly to the limit of its travel by means of a coiled spring 43 seated in a cavity 44 in the central portion of the die block 11. To limit the outward travel of the face plate, there are shown bolts 45, 46, rigidly carried by the face plate and slideable in openings 47, 48, in the die block. The amount of motion of the face plate 37 as well as its parallelism with the die block 11 is adapted to be adjusted by nuts 49, 50, and the adjustment may be secured by lock nuts 51, 52.

The heads of cap screws 35, 36, and the nuts 49, 52 are accessible within recesses 53, 54, in the ends of the die block 11. The members 38, 39, are shown as formed with tapering surfaces 55 in order to provide depressions in the brick having a form to readily receive the projections formed by the cavities 22, 23, in the upper die block and the members 38, 39, have enlarged por-

tions 56 at the base of the tapered portions 55, which, when the face plate 37 is depressed to the limit of its travel, completely fill the openings 41 in the face plate. By virtue of the single spring 43 for pressing the face plate 37 outwardly and separate bolts 45, 46, for limiting the travel of the face plate, the brick will be effectively freed from the surfaces of the members 38, 39.

10 To heat the die block 11 and the members 38, 39, there is shown an annular chamber 57 having cylindrical central portion 58 surrounding the spring receiving cavity 44. To conduct steam to the chamber 57 there are shown pipes 59, 60, having communication through passages 61, 62, with the chamber for the introduction and withdrawal of steam therefrom.

When a brick is placed between the upper and lower dies, enclosed in a frame not shown, and one of the die member is caused to move towards the other thereof, the relatively light springs 29 will first be compressed as the brick material flows into the 25 depressions 22, 23, with inward motion of the faces 24, 25, then the spring 43 will be compressed with projection of the members 38, 39, to form cavities in the lower face of the brick. The dies being heated and the 30 projections 38, 39, having considerable heat stored therein will form a slight skin upon the brick after which, the pressure being relieved, the spring 43 will first expand causing the members 38, 39, to be withdrawn 35 from the lower depressions, after which the plungers 27 will cause the brick to be freed from the surface of the face plate 19 when the brick may be readily removed.

The lower die block 11 is preferably cut away as shown at 63, 64, about the members 38, 39.

The provision herein described comprising a collapsible bottom for the projection forming depressions 22, 23, is very important in the successful and uninterrupted operation of the device. A difficulty heretofore has been the freeing of the projections formed upon the brick from the depressions which form the same, with a result that the 50 projections have broken away from the body of the brick and remained in the die, necessitating a closing down of the press to clear away the adhering material. By virtue of the collapsible bottoms 24, 25, this breaking away is avoided and the die being heated, a slight curing of the clay results, assisting in the freeing of the formed projections from the die. This is particularly important in the pressing of granular clay material such as is manipulated in the repressing of refractory brick.

Moreover by virtue of the fact that the projections will be formed upon the brick with the forcing of the plungers 24, 25, by 65 compression of the relatively light springs

29, before the stiff spring 43 is depressed, to cause the depressions in the brick to be formed, the projections will receive the greater amount of curing action and will be the more readily separated from the cavities. 70

At 65 in Figure 1, a mold to enclose the material while being pressed by the dies, is shown in dotted lines. A side elevation of a form of brick, which may be formed by the dies chosen to illustrate the invention, is 80 shown at 66 in Figure 8 of the invention.

Minor changes may be made in the physical embodiment of the invention within the scope of the following claims without departing from the spirit thereof. 85

I claim:

1. A brick die having a recess for the formation of a boss upon a brick, a collapsible bottom for said recess and means to press said bottom into the recess for separation of the formed brick from the die surfaces. 90

2. A brick die comprising in combination, a die plate having projection forming recesses therein, a second die plate having depression forming means, a perforation in said second named plate telescoping said depression forming means whereby to house said means flush with the surface of the plate and means operable by pressure upon the 100 plate to cause protrusion of the depression forming means. 95

3. A brick die comprising in combination, a plate having a projection forming cavity, means projecting through the bottom of said cavity and adapted to be forced inwardly flush with said bottom, a second plate having depression forming means telescopically received therein, means whereby the projection of said depression forming means and the recession of said means projecting into the cavity will be caused to operate when pressure is applied to said plates, said means acting to withdraw the depression forming means prior to the return to normal of the 110 means projecting into said cavity whereby to free a formed brick from the die. 115

4. A brick die comprising in combination, a plate having a projection forming cavity therein, a plunger pressed into said cavity through the bottom thereof by a relatively light spring, a second plate having an opening, a depression forming means housed in said opening, said perforated plate pressed to position flush with the end of said depression forming means by a relatively stiff spring whereby pressure upon a brick between said plates will first cause the formation of projections upon the brick with recession of the plunger into the cavity and will 125 130

later cause projection of said depression forming means with freeing of the brick from the plates by a reverse action.

5. A brick die comprising in combination, a plate having projection forming cavities therein, a plunger projecting through the bottom of each of said cavities and adapted to be forced into said plate to lie flush with the bottom of the cavity, means to cause said plungers to return to normal position whereby to free formed projections from said cavities and means to heat said plate and plungers.

6. A brick die comprising in combination, a plate having projection forming cavities therein, a second plate having perforations therein, means telescopically received in said perforations to form depressions in a brick, a block rigidly carrying said projection forming means, resilient means to press said plate away from said block and separate means to limit the action of said resilient means.

7. A brick die comprising in combination, a plate having projection forming cavities therein, a second plate having perforations

therein, means telescopically received in said perforations to form depressions in a brick, a block rigidly carrying said projection forming means, means acting against the center of said plate to press the plate away from the block and a plurality of means adjacent the periphery of the plate to limit such separation.

8. A brick die having a recess for the formation of a boss upon a brick, a collapsible bottom for said recess, means to press said bottom into the recess for separation of the formed brick from the die surfaces and means to heat said die.

9. A brick die comprising in combination, a die plate having projection forming recesses therein, a second die plate having depression forming means, a perforation in said second named plate telescoping said depression forming means whereby to house said means flush with the surface of the plate, means operable by pressure upon the plate to cause protrusion of the depression forming means and means to heat each of said die plates.
